UNITED STATES PATENT OFFICE.

WILLIAM A. FIFER, OF QUINCY, ILLINOIS, ASSIGNOR TO THE QUINCY SHOW CASE WORKS, OF QUINCY, ILLINOIS, A CORPORATION OF ILLINOIS.

DESIGN FOR A DISPLAY-CASE.

56,348.

Specification for Design.

Patented Oct. 5, 1920.

Application filed June 7, 1920. Serial No. 387,185. Term of patent 14 years.

To all whom it may concern:

Be it known that I, WILLIAM A. FIFER, a citizen of the United States, residing at Quincy, in the county of Adams and State of Illinois, have invented a new, original, and ornamental Design for a Display-Case, as shown in the accompanying drawing, forming part of this specification.

The design shown comprises an ornamental base portion 1; transparent end portions 1^a; transparent top portion 1^b; a transparent front portion 1^c; and within, and visible through the transparent front, top and end portions, is a cubical chamber 3 having a transparent top and transparent front

and end walls; and within the case and at opposite sides of the said cubical chamber are shelf portions 2. The interior of the case and of the chamber are all visible through the transparent top and front and end walls, and the whole case presents an ornamental pleasing appearance.

I claim:

The ornamental design for display case as shown and described.

WILLIAM A. FIFER.
